CLAIM

The ornamental design for an open-ended container, as shown and described.

DESCRIPTION

This application is also related to U.S. patent application Ser. No. 29/400,169, now U.S. Pat. No. D669,273, filed Aug. 24, 2011 and entitled “Open Ended Container,” to U.S. patent application Ser. No. 29/400,177 filed Aug. 24, 2011 and entitled “Open-Ended Container System,” to U.S. patent application Ser. No. 29/417,221, filed on Mar. 30, 2012 and entitled “Open-Ended Container,” to U.S. patent application Ser. No. 29/417,229, filed Mar. 30, 2012 and entitled “Open-Ended Container,” and to U.S. patent application Ser. No. 29/422,034, filed May 15, 2012 and entitled “Open-Ended Container System.”

FIG. 1 is a front perspective view of an open-ended container embodying my new design;

FIG. 2 is a top view of the open-ended container of FIG. 1;
FIG. 3 is a front view of the open-ended container of FIG. 1;
FIG. 4 is a side view of the open-ended container of FIG. 1;
FIG. 5 is a rear view of the open-ended container of FIG. 1;
and,

FIG. 6 is a bottom view of the open-ended container of FIG. 1.

The broken lines shown are included for the purpose of illustrating an environment of the article and form no part of the claimed design.
